UNITED STATES PATENT OFFICE

91,923

DESIGN FOR A CAP

Maria Constantine, New York, N. Y., and Conway
L. Atwater, Weston, Conn.

Application February 6, 1934, Serial No. 50,652

Term of patent 7 years

To all whom it may concern:

Be it known that we, MARIA CONSTANTINE and CONWAY L. ATWATER, citizens of the United States of America, and residents, respectively, of New York, in the county and State of New York, and of Weston, in the county of Fairfield and State of Connecticut, have invented a new, original, and ornamental Design for a Cap, of which the following is a specification, reference being had to the accompanying drawing, forming part hereof.

In the drawing:

Fig. 2 is a back view in perspective of the cap shown in Fig. 1.

We claim:

The ornamental design for a cap, as shown.

MARIA CONSTANTINE.
CONWAY L. ATWATER.
